UNITED STATES PATENT OFFICE

HIRAM K. WHITNER, OF CHICAGO, ILLINOIS.

REVERSIBLE BALANCE-WINDOW.

SPECIFICATION forming part of Letters Patent No. 658,818, dated October 2, 1900.

Application filed February 23, 1900. Serial No. 6,159. (No model.)

To all whom it may concern:

Be it known that I, HIRAM K. WHITNER, a citizen of the United States, residing in Chicago, in the county of Cook and State of Illinois, have invented a new and useful Improvement in Reversible Balance - Windows, of which the following is a specification.

My invention relates more particularly to that type of reversible windows having a detachable stile upon each side of a sash-frame and provided with a pivotal union, whereby said sash-frame and said stiles may be held in engagement in sashways of a balance-window.

The object of my invention is to supplement the construction shown and described in my application for Letters Patent designated Serial No. 731,906.

My invention consists in a novel construction of the component parts pertaining to a reversible balance-window and differing from said Serial No. 731,906 in features and functions such as developed themselves in a reduction to practice and having proven of practical value, the highest stage of perfection being attained in said reversible balance-window by the introduction of the adjuncts hereinafter shown and described. In a reduction to practice it will be found that the component parts of said reversible window will be held more firmly in their interlocked position centrally in the opening of said window by virtue of the beading and channeling hereinafter fully set forth and by virtue of an L-shaped journal adapted to engage with a journal-bearing of U form. Because of the relative positions held by the two functional limbs pertaining to said L-shaped journal when said sash-frame and said detachable stiles are in alignment in said improved windows with the beading and channeling registering I have an upright limb in the form of a journal-bead registering with a U-form journal-bearing, and I have a horizontal limb in the form of a pivot-pin projecting through said U-form journal-bearing and through said detachable stile, said upright limb having two functions, it being the base to said pivot-pin, (the horizontal limb,) and by virtue of its upright position it acts as a journal-lug, inasmuch as said journal-bead stands upon a beveled foot (hereinafter more generally designated bevel G') resting upon an elevated

journal-bearing, as hereinafter more fully shown, thereby relieving the pivot-pin of all violent shocks while removing the balanced sash-frame in the sashways. The horizontal limb of said L-journal member also has two functions. It is a pivot-pin whereby said pivotal-union members are held in engagement, and it is adapted to abut against the pulley-stile in order to hold said component parts pertaining to a reversible balance-window centrally in the opening of said window, and because of said latter function the free end of said horizontal limb will hereinafter be designated the "butt-end."

In this application in order to avoid prolixity I confine myself to a preferable method of beading and channeling that has the wide radial beading and the intermediate narrower beading upon the facing edge of the sash-frame and the wide longitudinal channeling and the intermediate narrower channel upon the detachable stile. With said beading supplemented by modifications in their construction I attain functions not otherwise obtainable. This will be manifest by referring to my accompanying drawings, forming part of this my specification, wherein like letters of reference refer to like parts in the various figures; and, moreover, the construction on both sides of said window being preferably similar I illustrate but one side of a portion of said sash-frame with its detachable stile in engagement in the sashway of a balance-window.

Figure 1 is a front elevation of part of a balance-window with the illustrated sash-frame in its normal vertical position. Fig. 2 is a view showing the same construction with the sash-frame partially reversed. Fig. 3 shows a method of constructing my beading on the facing edge of the sash-frame. Fig. 4 shows a method of constructing my channeling on the facing edge of the detachable stile. Fig. 5 shows a method of constructing the outwardly-facing edge of the detachable stile. Fig. 6 shows a method of constructing the pulley-stile when fixing to said detachable stiles interstice members. Fig. 7 shows a central longitudinal section of a sash-frame and a detachable stile with certain adjunct members pertaining thereto in engagement, with said interstice members omitted. Fig.

8 shows the same central longitudinal section in the first moment when said sash is being reversed. Fig. 9 shows a longitudinal horizontal section of a meeting-rail pertaining to an upper (outer) sash-frame in engagement with a cross-section of a detachable stile, also a cross-section of a parting-strip of a sashway. Fig. 10 is a side view of said parting-strip. Fig. 11 shows a side view of my journal-bearing of **U** form. Fig. 12 shows a detached member, designated hereinafter "interstice" member. Figs. 13 and 14 show views of my weight-chain anchor. Fig. 15 is a detached view of a bead-fender.

15 In Fig. 1, X is a section of a sash-frame. Z is the detachable stile. Y is the pulley-stile, A and C being positions occupied by interstice members. D is an interstice between said detachable stile and said pulley-stile. H' is the butt-end of the horizontal limb of an **L**-shaped journal member. (The latter shown in broken lines.)

In Fig. 2 sash-frame X is partially reversed, detachable stile Z is thrust laterally 25 toward pulley-stile Y primarily by the disengaging of the radial beads E and F from the respective longitudinal channels e and f, (the latter shown in broken lines,) said detachable stile Z being held in the depth of 30 the sashways by the disengaged upright limb of the **L**-shaped journal member. (The latter shown more fully in Fig. 8.) T is a predetermined-point indicator. t is another predetermined-point indicator. The interstice 35 members in positions A and C are shown in engagement with their respective recess a and c, the latter being also shown in Fig. 1.

Inasmuch as butt-end H' must have an unbroken smooth surface in the path of its 40 travel while abutting against the pulley-stile, reference should be had to Fig. 6, wherein it is shown how the recesses c c provide an unbroken path in the line of travel taken by said butt-end H' when said balance-window 45 is moved in its so-called "vertical" plane.

In Fig. 3 the facing edge of a sash-frame shows the radial beads E and F. G is the journal-bead. G² is a topmost extreme of said journal-bead widened to conform to the 50 radial bead E. G³ is a widened metal spur, (more fully shown and described hereinafter with reference to Fig. 7,) said spur being adapted to aid extreme G² in giving stability to the horizontal limb H of said **L**-shaped 55 journal member. F' is a metal bead-fender. E' is a metal bead-fender having in pivotal engagement catch Q, provided with a keeper Q' in the form of a spring.

In Fig. 4 I show how the retaining-plate i' 60 and i² in the journal-bearing of **U** form are inset (inlaid) by cutting into the facing of the walls of a channel cut primarily from one extreme to the other extreme of said detachable stile, said primary channeling being 65 elliptical in form, about one-fourth of an inch in depth and one inch in breadth. This inset cutting, being about one-eighth of an inch

in depth, narrows said primary channeling in conformity with the journal-channel g, the said retaining-plates i' and i² forming the 70 metal walls of said narrow journal-channel. h' is the journal-bearing proper, being an elevation pertaining to segment h². q is a catch-pin. q' is a slit adapted to receive catch Q.

75 In Fig. 5, A A A being positions occupied by three interstice members, the two placed laterally should be secured flush with the side edges of said detachable stile, while the interstice member in position of the middle A 80 should always occupy a central position on said outwardly-facing edge of the detachable stile in order that said middle interstice member may move in the unbroken path provided for the butt-end of the horizontal limb of the 85 **L**-shaped journal member, C C being positions occupied by two interstice members for the above obvious reasons. W is my improved weight-chain anchor. V' V' are the overhanging points of the chain-pin V, forced 90 into the walls of the three-fourth-of-an-inch-in-diameter boring w and of a depth about three-eighths of an inch. Said weight-chain anchorage occupies a relative position in the balance-window that devices of a like nature 95 occupy when securing cords directly to a sash-frame. h⁴ is a piercing elliptical in form, with its longest diameter upright in said detachable stile and adapted to sleeve with the horizontal limb of the journal member. An ordinary wooden plug temporarily inserted into the space between said horizontal limb and the upper segment of said piercing h⁴ will keep the said detachable stile immovable in contact with the sash-frame, 100 inasmuch as said upright limb with said adjunct bevel cannot escape the journal-bearing, while said horizontal limb is obstructed and prevented from rising in said elliptical piercing, thereby making it possible to transport said component parts as a one-piece sash.

105 In Fig. 6 the recess a extends the full width of the sash, inasmuch as it is not in the path of any member requiring a smooth surface at this point. Not so with the recess c c. Said 115 sections of said recess not only occupy positions relatively opposed to the interstice members, being in positions C C, but they occupy positions on each side of the path of travel of both butt-end H' and of middle A, 120 hereinbefore described.

In Fig. 7, E' is a metal bead-fender conforming to the radial bead E and holding in pivotal engagement catch Q, provided with a keeper Q'. F' is a metal bead-fender conforming to the radial bead F. G, G', G², and H pertain to said **L**-shaped journal member, hereinbefore described. b is a modified butt-end of said horizontal limb, provided with a threaded shank adapted to engage with a nut 130 B, whereby said butt-end of said horizontal limb of the **L**-journal member may be made adjustable. Bevel G' is in engagement with the journal-bearing, with the upright limb of

said L-journal member wholly in engagement with said journal-bearing of U form, thereby taking all strain off the horizontal limb, which latter in this position is simply an abutting member and not a journal member integrally. 5 h is a tapering segment of a dowel, ending in an anchor-fluke N, said dowel h being adapted to be inserted into piercing h⁴, said anchor-fluke N being adapted to engage with niche n, cut into the wall of said piercing h⁴, whereby the journal-bearing of U form may be anchored to said detachable stile Z. Dowel P inserted into sloping piercing p anchors said L-journal member to said sash-frame x and 10 forms a junction between said L-journal member and said widened metal spur G³, provision being made for the interlocking of elevation h' and segment h³ or the engagement of said latter members with the notch formed 15 by the hereinbefore-described bevel G' and said metal spur G³. Dowel P' inserted into sloping piercing p' anchors bead-fender E'. Dowel P² inserted into sloping piercing p² anchors bead-fender F', and catch Q is in 20 engagement with catch-pin q. The latter is in the form of a rivet crossing through the detachable stile Z from side to side just beyond the depth of the longitudinal channel e.

In Fig. 8 catch Q is disengaged from catch-pin q, the beading and channeling is disengaged, the journal-bead is withdrawn from said journal-bearing of U form, and the axis of the horizontal limb occupies a more elevated position, together with the component 30 parts pertaining to said sash-frame, inasmuch as said disengaging lateral movements have brought a section of the horizontal limb of said journal member, unbroken in its periphery, to rest upon said elevation of the journal-bearing of U form. In this position said horizontal limb is made the integral journal. Hence I preferably use the term "L-shaped journal member," because of this alternate shifting of said journal function from one 40 limb to the other limb of said journal member. Hence it will be obvious that when the reversed sash is restored to its normal position a broken or beveled portion of said periphery will contact with said elevated journal-bearing, and in view of these contacting surfaces the component parts pertaining to said sash-frame will descend a limited distance by a gravitating force.

In Fig. 9, F is the lower radial bead of the 50 upper (outer) sash-frame. K is the meeting-rail. K' is the check-lip of said meeting-rail. K² is the extension of said check-lip, said check-lip extension having the double function of a weather-strip and a striking-stop, 55 the latter contacting with detachable stile Z, the function of a weather-strip when in opposition with interstice member s' pertaining to parting-strip S.

In Fig. 10, S is a parting-strip holding in fixed 60 engagement interstice member s' directly in opposition with check-lip K', pertaining to said upper sash.

In Fig. 11, l² is a side view of one of the securing-plates pertaining to the journal-bearing of U form. h is the tapering dowel-segment 70 N is the anchor-fluke. h³ is the segment that divides transversely the primary channeling.

In Fig. 12 my interstice member is shown detached, said member being in positions A 75 and C when fixed to the outwardly-facing edge of said detachable stiles, and when said interstice member is fixed to said parting-strip it is designated s'.

In Figs. 13 and 14, W is my weight-chain 80 anchor, especially adapted to restricted quarters such as are found in the detachable stiles of this type of windows. W' is an aperture partially in the periphery and partially in the base-plate of said anchor member, said aperture being adapted to receive the free end of said weight-chain. V is a chain-pin. V' V' are overhanging points adapted to be inserted (forced) into the walls of a three-fourths-inch 85 boring.

I show my bead-fender holding in pivotal engagement catch Q in but one position. It will not be a departure from the spirit of my invention to place said bead-fender at each extreme of said beaded members. 90

Having thus fully described my invention, I will now in claims point out what is new and novel.

1. In a reversible balance-window the combination, with a sash-frame and two detachable stiles, of an L-shaped journal member, provided with a bevel-foot, and adapted to engage with a journal-bearing of U form and means whereby said sash and said stiles may be held in relative positions in the opening 100 of said window, substantially as and for the purpose set forth.

2. In a reversible balance-window the combination, with a sash-frame and two detachable stiles, of an L-shaped journal member 110 having a pivot-pin adapted to abut against a pulley-stile, said journal member being provided with a bevel-foot, a journal-bearing of U form adapted to engage with said journal member, a pulley-stile provided with a smooth 115 surface in the path of travel of the free end of said horizontal limb and means whereby said sash and said stiles may be held in relative positions in the opening of said window, substantially as and for the purpose set forth. 120

3. In a reversible balance-window, the combination, with a sash-frame and two detachable stiles, of an L-shaped journal member having a pivot-pin adapted to abut against a pulley-stile, said journal member being provided with a bevel-foot, a journal-bearing of U form adapted to engage with said journal member, a pulley-stile provided with relatively-placed recesses adapted to engage with interstice members of a detachable stile, a 125 detachable stile having on its outwardly-facing edge three interstice members near the lower extreme and two interstice members near the upper extreme, said interstice mem-

bers being adapted to engage with said recesses at a predetermined point, a predetermined-point indicator secured to a detachable stile and a predetermined-point indicator secured to a sashway-stop and means whereby said reversible window may be balanced in sashways in said window, substantially as and for the purpose set forth.

4. In a reversible balance-window, the combination, with a sash-frame and two detachable stiles, of an L-shaped journal member having a pivot-pin provided with an adjustable free end adapted to abut against a pulley-stile, said journal member being provided with a bevel-foot, a journal-bearing of U form adapted to engage with said journal member, a pulley-stile provided with a smooth surface in the path of travel of the free end of said pivot-pin, said sash-frame being provided with a bead-fender having in pivotal engagement a catch, said catch being provided with a keeper, said detachable stile being provided with a catch-pin adapted to engage with said catch as a means whereby said sash-frame and said detachable stiles may be immovably interlocked, and means whereby said reversible window may be balanced in sashways, substantially as and for the purpose set forth.

5. In a reversible balance-window the combination with a sash-frame and two detachable stiles, of an L-shaped journal member having a pivot-pin adapted to abut against a pulley-stile, said journal member being provided with a bevel-foot, a journal-bearing of U form adapted to engage with said journal member, said journal-bearing being provided with a tapering dowel having an anchor-fluke adapted to engage with the walls of an elliptical piercing in a detachable stile, a detachable stile provided with a piercing elliptical in form and adapted to hold in fixed engagement said dowel and said fluke, said piercing being adapted to receive said pivot-pin pertaining to said L-shaped journal member, substantially as and for the purpose set forth.

6. In a reversible balance-window, the combination, with a sash-frame and two detachable stiles, of an L-shaped journal member having an upright limb and a pivot-pin and provided with a bevel-foot, said upright limb being in the form of a journal-bead and adapted to engage with a journal-channel, said pivot-pin being provided with a butt-end adapted to project through a piercing in a detachable stile, thereby enabling said pivot-pin to abut against a pulley-stile, a journal-bearing of U form adapted to engage with said upright limb and with said bevel pertaining to said journal member, said journal-bearing being provided with a tapering dowel having an anchor-fluke adapted to be inserted in said piercing, a detachable stile provided with a piercing elliptical in form having a niche in the walls of said piercing adapted to engage with said anchor-fluke, and means whereby said reversible window

may be balanced in sashways in said window, substantially as and for the purpose set forth.

7. In a reversible balance-window, the combination, with a sash-frame and two detachable stiles, of an L-shaped journal member having an upright limb and a pivot-pin and provided with a bevel-foot, said upright limb being in the form of a journal-bead, its top-most extreme being widened in conformity with a radial bead pertaining to said sash-frame, said journal member being provided with a dowel adapted to engage with a sloping piercing in said sash-frame as a means whereby said journal member may be fixed to the facing edge of said sash-frame, a journal-bearing of U form adapted to engage with said journal member and means whereby said sash and said stiles may be balanced in sashways in said window, substantially as and for the purpose set forth.

8. In a reversible balance-window, the combination, with a sash-frame and two detachable stiles, of an L-shaped journal member having an upright limb and a pivot-pin and provided with a bevel-foot, said upright limb being in the form of a journal-bead, its top-most extreme being widened in conformity with the radial bead pertaining to said sash-frame, a sash-frame provided with a metal bead-fender secured to the extreme of its facing edge, said metal bead-fender conforming to the shape of said radial bead pertaining to said sash-frame as a means whereby a radial bead may be fitted to the facing edge of said sash-frame in alternate sections of metal and of wood, substantially as and for the purpose set forth.

9. In a reversible balance-window, the combination, with a sash-frame and two detachable stiles, of an L-shaped journal member having an upright limb and a pivot-pin and provided with a bevel-foot, said upright limb being in the form of a journal-bead, its top-most extreme being widened in conformity with a radial bead pertaining to the sash-frame, a sash-frame having a metal bead-fender conforming to the shape of said radial bead, said bead-fender having in pivotal engagement a catch adapted to engage with said detachable stile, and being provided with a keeper, a detachable stile provided with a catch-pin adapted to engage with said catch as a means whereby said detachable stile may be securely locked to said sash-frame, substantially as and for the purpose set forth.

10. In a reversible balance-window, the combination, with a sash-frame and two detachable stiles, of an L-shaped journal member adapted to engage with a journal-bearing of U form, a journal-bearing of U form having an elevated bearing and provided with a dowel adapted to engage with a detachable stile, a detachable stile provided with a piercing adapted to engage with said dowel, said detachable stile being provided with another piercing adapted to hold in fixed engagement

a weight-chain anchor, as a means whereby said sash and said stile may be suspended in sashways, substantially as and for the purpose set forth.

5 11. In a reversible balance-window, the combination, with a sash-frame and two detachable stiles, of an L-shaped journal member having an upright limb in the form of a journal-bead and a horizontal limb in the form 10 of a pivot-pin, said journal member having a bevel, said pivot-pin being provided at its free end with a threaded stem adapted to engage with a nut, a nut adapted to engage with the free end of said pivot-pin as a means 15 whereby said sash-frame and said stiles may be held adjustably in the center of the opening of said window, substantially as and for the purpose set forth.

12. In a balance-window, the combination, 20 a sash-frame X, a detachable stile Z, a pulley-stile Y, a journal-bearing of U form having an elevated bearing h', adapted to engage with an L journal member, an L journal member having a journal-bead G provided 25 with a bevel G' and having a horizontal limb H provided with a butt-end H' adapted to engage with said pulley-stile.

13. In a balance-window, the combination, 30 a sash-frame X, a detachable stile Z having interstice members fixed to its outwardly-facing edge, three of said members being fixed in a relative position designated A, two of said members being fixed in a relative position designated C, a journal-bearing of U 35 form having an elevated bearing h' adapted to engage with an L journal member, an L journal member being provided with a butt-end H' adapted to engage with a pulley-stile, a pulley-stile Y provided with recess a and two 40 recesses c, c adapted to engage with interstice members being in positions A and C, C respectively at predetermined points.

14. In a balance-window, the combination, 45 a sash-frame X, a detachable stile Z provided with a predetermined-point indicator T and having an elliptical-shaped piercing h⁴, said detachable stile Z being provided with interstice members fixed to its outwardly-facing edge in positions A and C, a journal-bearing 50 of U form having an elevated bearing h', a journal member being provided with a butt-end H' adapted to engage with a pulley-stile, a pulley-stile Y being provided with recess a and recess c adapted to engage with said 55 interstice members fixed in relative positions A and C, a casing-stop provided with predetermined-point indicator t.

15. In a balance-window, the combination, 60 a sash-frame X having in fixed engagement a journal member, an L-shaped journal member, a detachable stile Z having in fixed engagement a journal-bearing, a journal-bearing of U form in fixed engagement in a piercing h⁴, a butt-end H' protruding through said 65 piercing h⁴ and adapted to engage with a pulley-stile, a pulley-stile Y and a parting-strip

S, said parting-strip being provided with an interstice member s'.

16. In a balance-window, the combination, 70 a sash-frame X having in fixed engagement an L-shaped journal member, an L-shaped journal member adapted to engage with a journal-bearing, a detachable stile Z having an elliptical-shaped piercing h⁴ provided with a niche n cut in the wall of said piercing, a 75 journal-bearing of U form having a dowel h adapted to be inserted in said piercing h⁴, said dowel being provided with an anchor-fluke N, said anchor-fluke being adapted to engage with said niche n. 80

17. In a balance-window, the combination, 85 a sash-frame X having a piercing p, a detachable stile Z provided with a journal-channel g, an L-shaped journal member having a journal-bead G and a horizontal limb H, said L- shaped journal member being provided with a dowel P adapted to be fixedly engaged with said piercing p, a journal-bearing of U form having metal retaining-plates i' and i² adapted to be inset in the facing edge of said detachable stile Z. 90

18. In a balance-window, the combination, 95 a sash-frame X provided with a piercing p², a detachable stile Z, an L-shaped journal member, a journal-bearing of U form, a bead-fender F' having a dowel P² adapted to engage with said piercing p².

19. In a balance-window, the combination, 100 a sash-frame X provided with a piercing p', a detachable stile Z provided with a catch-pin q, a bead-fender E' having a catch Q and provided with a dowel P' having in fixed engagement keeper Q', said catch Q being adapted to engage with said catch-pin q and said dowel P' being adapted to engage with said 105 piercing p'.

20. The combination, a sash-frame, a detachable stile, a bead-fender having in pivotal engagement catch Q and provided with a dowel—said dowel being adapted to hold in 110 fixed engagement keeper Q', and a catch-pin q adapted to engage with said catch.

21. In a balance-window, the combination, 115 a sash-frame provided with a meeting-rail K, a check-lip extension K² and provided with a beading F', a parting-strip S provided with an interstice member s' and a detachable stile Z adapted to engage with said bead and with said check-lip extension.

22. In a balance-window, the combination, 120 a sash-frame X provided with the radial beads E and F and having a piercing p, an L-shaped journal member consisting of a journal-bead G and a horizontal limb H having a butt-end H', said L-shaped journal member being provided with a dowel P adapted to engage with said piercing p, a detachable stile Z provided with longitudinal channels e and f, and having a journal-channel g, said detachable stile Z being provided with a piercing h⁴ having a 125 niche n, a journal-bearing of U form having an elevated bearing h' and provided with a 130

dowel *h* having an anchor-fluke *N* whereby said journal-bearing may be held in fixed engagement in said piercing *h*⁴, said detachable stile being provided with another piercing 5 designated *w* adapted to hold in fixed engagement a weight - chain anchor, as a means whereby said sash and said stiles may be balanced in sashways in said window.

23. In a balance-window, the combination, 10 a sash-frame *X* having a radial bead *E* provided with a bead-fender *E'*, said sash-frame having a radial bead *F* provided with a bead-fender *F'*, a journal member adapted to engage with a journal-bearing, a journal-bearing 15 of **U** form having inset plates *i'* and *i''* adapted to be fixed to the facing edge of a detachable stile, a detachable stile *Z* having longitudinal channels *e* and *f*, said detachable stile having fixed to its outwardly-facing 20 edge three interstice members in position *A* and two interstice members in position *C*,

said interstice members being adapted to engage with a pulley-stile, a pulley-stile *Y* provided with a recess *a* and two recesses *c*, *c* adapted to engage respectively with said interstice members at a predetermined point. 25

24. In a balance-window, the combination, a sash-frame *X* having the radial beads *E* and *F* and having in fixed engagement an **L**-shaped journal member, a detachable stile *Z* 30 having the longitudinal channels *e* and *f* and having in fixed engagement a journal-bearing of **U** form, a parting-strip *S* provided with an interstice member *s'*, said sash-frame being provided with a check-lip *K'* having an extension *K*². 35

In testimony whereof I affix my signature in the presence of two witnesses.

HIRAM K. WHITNER.
